CLAIM

The ornamental design for a combined riflescope and camera, as shown and described.

DESCRIPTION

FIG. 1 is a perspective view of a combined riflescope and camera, showing my new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof, the bottom view being identical in appearance to the top except for the film winding knob which appears on the top and not on the bottom.

FIG. 6
